CLAIM

The ornamental design for a simulated shock absorber body, as shown and described.

DESCRIPTION

FIG. 1 is a front view of the simulated shock absorber body, illustrating the simulated shock absorber body connected to an exemplary vehicle;

FIG. 2 is an enlarged top view of the simulated shock absorber body, with the bottom view being a mirror image thereof;

FIG. 3 is a left side view of the simulated shock absorber body shown in FIG. 2;

FIG. 4 is a right side view of the simulated shock absorber body shown in FIG. 2;

FIG. 5 is a front view of the simulated shock absorber body shown in FIG. 2; and,

FIG. 6 is a back view of the simulated shock absorber body shown in FIG. 2.

The broken line showing of portions of a simulated shock absorber body in FIGS. 1–6 and a vehicle in FIG. 7 in FIGS. 1–5 are included for the purpose of illustrating environment and forms no part of the claimed design.
